WINDOW

Andrew C. Thompson, Miami Beach, Fla.

Application December 10, 1936, Serial No. 115,256

20 Claims. (Cl. 189—69)

This invention relates to windows of the general character of that shown in my co-pending application, Serial No. 103,186, filed September 29, 1936, of which this application is a continuation in part.

Like the structure of my aforesaid application, the object of the present invention is to provide an improved type of window consisting of a plurality of horizontally hinged sections adapted to 10 be swung upwardly and outwardly to open position or to be swung downwardly and inwardly in such manner that the lower edge of each window section has overlapping and abutting engagement with the next lowermost section, though 15 the structure of the present application involves the inclusion of resilient weather strips at the point of engagement, in a manner not shown in the parent application 103,186.

As this description proceeds, it will be seen 20 that the window of this application incorporates the following features and advantages, viz: it will exclude rain, even when open; it will provide one hundred percent ventilation, i. e. its members may be moved to such position as to offer 25 substantially no obstruction to the free entry of air; it may be easily adjusted to regulate and control the draft therethrough; it will exclude burglars even when the window is open; it is so constructed as to permit the operation of a gang 30 of window units in unison with a counterbalanced control which renders it possible to operate the windows with very little effort; it is so constructed as to permit easy cleaning of the windows on both sides from within the room; it presents a modern and pleasing appearance; it is 35 so constructed that it may be entirely contained within the thickness of the walls in all positions of adjustment; it may be constructed of standardized units, thus yielding flexibility, both as 40 to the height and the ganging of the windows; it provides multiple shades suitably protected and housed and provides full ventilation even when the shades are drawn for excluding the sun or vision; it provides means for actuating all of 45 the shades in unison under the influence of a single control, and it eliminates the customary flutter and noises incidental to the use of conventional shades and Venetian blinds.

Further, by the use of resilient weather strips 50 at the point of engagement of the lower portion of one glass pane with the top frame member of the next lower window section, I am able to bring about such cushioning engagement of the various window sections with each other as to 55 not only effectively exclude rain, even in driving

rain storms, but I am able to eliminate much of the customary rattle incident to the use of windows of this general type.

Further, by the use of resilient weather strips bearing against the ends of the window sections 5 and additional weather strips overlapping the adjacent ends of window sections that are arranged in gangs, I am able to provide a relatively tight window in bad weather, while providing for extremely free and complete ventilation in 10 good weather. Further objects and advantages of the invention will be set forth in the detailed description which follows.

In the accompanying drawings:

Figure 1 is a vertical sectional view through a 15 window, illustrating an improved actuating and counterbalancing mechanism, hereinafter described;

Fig. 2 is a fragmentary vertical sectional view 20 of a structure similar to that illustrated in Fig. 1 but wherein individual shades for the several window sections are employed;

Fig. 3 is an enlarged detail vertical sectional view through one of the window sections;

Fig. 4 is a front elevation of one of the window 25 sections;

Fig. 5 is a diagrammatic front elevation illustrating how the windows may be arranged in gangs;

Fig. 6 is a view illustrating one of the spring 30 wound shade rollers;

Fig. 7 is an enlarged side elevation of the lower corner of one of the window sections;

Fig. 8 is a horizontal sectional view on line 35 8—8 of Fig. 7;

Fig. 9 is a fragmentary horizontal sectional view of a structure wherein two gangs of windows are arranged side by side as illustrated diagrammatically in Fig. 5, and

Fig. 10 is an enlarged view of the structure of 40 Fig. 9.

Like numerals designate corresponding parts in all of the figures of the drawings.

Referring now to Fig. 1, 5 designates a building wall having a window opening 6 formed therein. A plurality of window sections 7 are pivoted at 8 to whatever material may constitute the side walls of the opening 6, this, of course, being a mere matter of choice upon the part of the builder. Ears 9, rigidly connected to the window 50 sections 7, are in turn pivoted at 10 to a vertically movable rod 11.

The upper end of this rod is connected at 12 to a segmental gear 13, said gear being adapted to be rocked about its pivotal mounting 14 by 55

means of a worm 15. This worm carries a pulley 16 over which an operating cord or chain 17 is passed. Handles 18 and 19 provide means for drawing upon the cord or chain in one direction 5 or the other to rotate worm 15 and consequently to rock gear 13. This in turn swings the window sections upon their pivots 8, through the medium of the rod 11, to move said windows to either open or closed position in a manner common in this 10 type of window.

The lower end of rod 11 is pivotally connected at 20 to a triangular plate 21, and this plate is pivoted at 22 in a position corresponding to the position of the pivots 8. A spring 23 is secured 15 at one of its ends to the window sill 24, and its opposite end is connected at 25 to the apex of plate 21. A particular advantage arising from this construction is that the spring not only aids in counterbalancing the weight of the window 20 sections, but its effective force is varied as the resistance to the movement of the window sections varies.

In other words, there is more resistance to the movement of the windows under the influence of 25 the strength of the operator as said windows approach the horizontal than there is at the beginning of the movement of the windows when they lie nearly vertical. Thus, when the windows are closed, pivot 25 lies more nearly in alignment 30 with pivot 22 than when the windows are halfway open or in the position illustrated in Fig. 1. It will be observed that as the window sections move from the position of Fig. 1 upwardly or farther toward the horizontal, pivot 25 moves farther 35 toward the right and consequently, the spring 23 will increasingly exert its effective force.

Referring now more particularly to Figs. 2 and 3, the actuating means for the several window sections are substantially the same and the same 40 reference characters have been applied. However, in this form of the invention, window shades are provided for the several window sections. These shades are indicated at 26. They are wound upon conventional spring wound rollers 45 21, one of which is indicated in Fig. 6. These rollers differ from ordinary shade rollers only in not being provided with ratchets for holding them against return movement. They are so arranged as to always tend to wind the shades upon them.

50 The window sections comprise the glass panes 28, having the free lower edges 28a. The top edges of these panes are received in the head frame members 29, and their side edges are received in the side frame members 30.

55 By referring to Fig. 8, it will be seen that these side frame members are of channel formation and that the panes 28 are bound therein by suitable packing 31. However, the packing does not completely fill the channels of the members 60 30, so that sufficient space is left upon the inner sides of the windows for the reception of the side edges of the shades 26 and for the actuating cords 32 of said shades, it being understood that 65 these cords are attached to the lower edges of the shades, pass downwardly through the channels of the side frame members 30 upon the inner sides of the panes, thence over pulleys 33, disposed at the bottom of said members 30, thence upwardly through the channels of the 70 side frame members 30 to and through passages 34 in the head frame members 29.

All of the cords of all of the shades may be wound upon a roller 35 or shaft and pulleys, to which turning motion may be imparted by cord 75 36 and handle 37. Any suitable means may be

employed for holding the cord 36 in the position to which it is drawn, such, for example, as a common cleat or ratchet attached to roller or shade, it being understood that whenever the handle 37 is released, the rollers 27 will act to 5 draw the shades back upon themselves.

The head frame members 29 are continued downwardly, as indicated at 29a, to form protective housing for the shades. Resilient metallic strips 38 are secured to the head frame 10 members, and the panes of the upper sections contact these weather strips upon the next lower sections when the windows are moved to closed position under the influence of the worm gearing hereinbefore described.

15 The head frame members are provided with ears 9a, corresponding to the ears 9, and these ears are pivoted at 10a to operating strips 11 in the manner hereinbefore set forth. These head frame members are provided with pivots 8a, corresponding to the pivot mountings of the window sections hereinbefore described.

20 Fig. 5 illustrates how two vertical rows of window sections may be arranged in gangs in a metallic frame 39 of any suitable configuration in 25 cross section, such, for example, as the conventional angle iron commonly employed for metallic window frames. The center bar 39a may likewise be of any suitable shape in cross section, such for example as T-shape.

30 The actuating mechanism for windows arranged in gangs may be such as is illustrated in Fig. 10, where actuating rods or bearings 11b, corresponding in function to the rod 11 of Fig. 1, are disposed upon the opposite sides of the 35 web 39c of the central T-frame member, these rods being connected to the ears 9b of the window sections 7b.

35 In this case, the pivots for connecting the rods 11b to the ears 9b and indicated at 40, are 40 extended through arcuate slots 41 of the web or rib 39c in such manner that the actuation of one rod 11b will serve to actuate the other rod 11b and thus both banks of windows may be actuated from a common actuating member such as 45 segmental worm gear 13, worm 15 and pulley 16, in the manner described with respect to Fig. 1. The upper and lower arcuate slots 41 permit the passage of the pivots 12a and 20a, which connect the upper and lower ends of the bars respectively.

50 Referring now to Fig. 9, 42 indicates resilient metallic weather strips secured at 43 to the angle iron frame 39 and bearing yieldingly upon the ends of the window sections to aid in preventing the entry of wind or rain at that point. I 55 may further employ resilient metallic weather strips 45 which overlap the adjacent ends of the window sections 7b and are fixed to one of said sections as indicated at 46, it being understood that there will be one of these weather strips for 60 each horizontally aligned pair of window frame sections.

65 It is to be understood that the invention is not limited to the precise construction shown and described, but that it is intended to cover the principles involved within the scope of the appended claims.

Having described my invention, what I claim is:

70 1. An actuating means for a window comprising a plurality of horizontally pivoted window sections, consisting of a common actuating bar pivotally connected to said sections, and means for actuating said bar comprising a worm gear to which the bar is pivoted, a worm engaging 75

said worm gear and manually operable means for actuating the worm.

2. A structure as recited in claim 1, wherein said manually operable means comprises a pulley 5 upon the shaft of the worm, and a flexible strand passing over said pulley and extending downwardly to a point within reach of the person operating the window.

3. A structure as recited in claim 1, in combination with a spring acting upon said bar in 10 a manner to counterbalance the weight of the window sections.

4. A structure as recited in claim 1 in combination with a substantially triangular plate, 15 pivoted at one of its apices in line with the pivotal mountings of the window sections, pivoted at another of its apices to said common actuating rod, and being connected at its third apex to one end of a spring, the other end of the spring 20 being fixed to a portion of the window frame.

5. In combination with a group of window sections comprising frames and transparent panes, means for pivotally mounting said sections adjacent their upper ends and at points 25 substantially equidistantly spaced from each other, ears extending inwardly beyond the said pivot points of each of said sections, and a rod to which said ears are pivotally connected, means for imparting vertical movement to said rod comprising a segmental worm gear with which the 30 said rod has pivotal engagement, a worm engaging the worm gear, a pulley upon the shaft of the worm gear, a strand passing over said pulley, and handles carried by said strand.

35 6. A structure as recited in claim 5 in combination with a member to which the lower end of said rod is pivotally connected, means for pivotally mounting said member, and a tension spring engaged with said member at such point 40 that in the opening movement of the window sections, the point of engagement of said spring with said member moves further out of vertical alignment and more into horizontal alignment with the pivot point of said member.

45 7. A structure of the character described comprising a plurality of banks of horizontally pivoted window sections, a central mullion by which said sections are supported, bars pivotally connected to the window sections of the respective 50 banks, and means for imparting endwise movement to the bars of both banks of windows in unison.

55 8. A window of the character described comprising a pair of vertical banks of horizontally pivoted window sections and a mullion by which said banks of windows are separated, an ear carried by each of the window sections, a vertically movable rod for each of the banks of windows, there being one of said rods upon each side of 60 the separating mullion, said mullion being provided with a plurality of arcuate slots, pivots connecting said bars and said ears and movable in said slots, and means for imparting endwise movement to one of said bars.

65 9. A structure as recited in claim 8 wherein the said bar actuating means comprises a segmental worm gear to which said bars are pivoted, a worm engaged with said worm gear, and means located exteriorly of the mullion for imparting turning movement to the worm.

70 10. In a window of the character described, the combination of a plurality of horizontally pivoted window sections, each comprising a top frame member and a pane having a free lower edge, of a resilient weather-strip carried by each

of the top frame members, with which the pane of the next higher window section engages when the windows are closed.

11. A structure as recited in claim 10, wherein the top frame members are provided with overhanging, inclined front face portions, said resilient weather strips extending along and being backed up by said overhanging portions of the top frame members. 5

12. A structure of the character described comprising a plurality of horizontally pivoted window sections, a spring actuated shade roller carried by each of said sections and located upon the inner side thereof, shades upon said rollers, cords at the opposite ends of the window sections, 15 an elongated roller upon which all of the cords of all of the shades are wound, and means for imparting turning movement to said roller.

13. A structure as recited in claim 12 wherein the means for imparting turning movement to 20 the roller comprises a strand wound thereon and a handle for drawing upon the strand, turning movement of the shade roller, under the pull of said strand, drawing upon the shades to withdraw them from the shade rollers, said shade 25 rollers being spring wound in a direction to resist the withdrawal of the shades therefrom.

14. A window unit comprising a head frame member and a pair of side frame members, ears carried by the head frame member extending 30 rearwardly therefrom at the upper portion thereof, said head frame member being shaped to form a housing, a spring actuated shade roller in said housing, a glass pane seated in channels formed in the head and side frame members, 35 packing in the channels of the side frame members which only partially fills said channels, to leave passages within the side frame members upon the opposite sides of the glass pane, a shade upon said shade roller, cords attached to said 40 shade and passing downwardly upon the inner side of the pane within the channel of the side frame members, thence over anti-friction devices at the bottom of the side frame members, 45 thence upwardly through the channels of the side frame members outside of the glass, and thence through the head frame member, and resilient weather strips upon the head frame members outwardly of the point at which said cords pass through the head frame member. 50

15. In a window construction of the character described, the combination with a plurality of horizontally pivoted window sections and a supporting frame by which they are carried, of resilient weather strips secured to the frame and having free portions which bear resiliently 55 against the ends of the said pivoted window sections.

16. A window of the character described comprising a plurality of pairs of horizontally pivoted window sections, the sections of each pair being horizontally aligned with each other, and a resilient weather strip secured to one of said window sections of the pair and overlapping and bearing upon the edge of the companion window 65 section of the pair.

17. In a window construction, a pair of banks of windows, each comprising a plurality of horizontally pivoted window sections, a separating mullion between the sections of the two banks, 70 ears carried by the said window sections, bars to which said ears are pivoted, there being one of said bars upon each side of the separating mullion, the pivots between the said bars and ears passing through the said mullion and being 75

common to the bars and ears upon both sides of said mullion, so that all of the windows of both banks may be adjusted simultaneously and in unison.

5. 18. A structure as recited in claim 17 in combination with resilient weather strips, one for each of the horizontally aligned window sections of the respective pairs of banks of windows, said weather strips being carried by one of the window sections of a horizontally aligned pair and bearing yieldingly upon the edge of the companion window section of said pair.

10. 19. A structure of the character described comprising a plurality of banks of horizontally pivoted window sections, a central mullion by which said sections are supported, vertically movable bars, one upon each side of said mullion, members mounted to turn, located at the top and bottom of said bars, means for imparting turn-

ing movement to one of said members, pivotal connections between the bars and said members and between the bars and the window sections, at least one of said pivotal connections being common to both of said bars, so that said bars 5 are caused to move in unison.

20. A window of the character described comprising a pair of vertical banks of horizontally pivoted window sections and a mullion by which said banks of windows are separated, a vertically 10 movable bar for each of the banks of windows, there being one of said bars upon each side of the separating mullion, pivots connecting said bars and passing through said mullion, and means for imparting endwise movement to one 15 of said bars, the window sections of each bank being pivotally connected to their corresponding bar.

ANDREW C. THOMPSON.
